UNITED STATES PATENT OFFICE.

CHARLES J. STABERG, OF NEW YORK, N. Y.

DESIGN FOR A PUZZLE-BOX.

SPECIFICATION forming part of Design No. 29,905, dated December 27, 1898.

Application filed November 19, 1898. Serial No. 696,948. Term of patent 3½ years.

To all whom it may concern:

Be it known that I, CHARLES J. STABERG, of the city of New York, borough of Brooklyn, in the county of Kings and State of New York, have invented and produced a new and original Design for a Puzzle-Box, of which the following is a full, clear, and exact description.

Reference is to be had to the accompanying drawings, forming a part of this specification, in which similar characters of reference indicate corresponding parts in all the figures.

Figure 1 is a plan view of the puzzle-box, showing my design. Fig. 2 is a cross-section of the same on the line 2 2 in Fig. 1, and Fig. 3 is a rear sectional elevation of the same on the line 3 3 in Fig. 1.

The design in its entirety consists of a box A in imitation of a pawnshop and approximately circular in shape, said box having a transparent cover A' and also having an en-

trance B, a door C, and L-shaped partitions D D' between the door and the side wall of the box to represent show-cases, the bottom of the box being ornamented by the illustration of a store-counter, the upper portion of a person appearing above the counter, a projection E rising from the bottom in close proximity to the door, and a raised strip F appearing vertically in the partition D adjacent to the free end of the door.

The leading feature of the design consists of a box having an entrance, a door, a projection, and a strip.

I claim—

The design for a puzzle-box, as herein shown and described.

CHARLES J. STABERG.
